UNITED STATES PATENT OFFICE.

HARRY L. COMPTON, OF WASHINGTON, DISTRICT OF COLUMBIA, ASSIGNOR TO AMERICAN DAIRY SUPPLY COMPANY, OF WASHINGTON, DISTRICT OF COLUMBIA, A CORPORATION OF MAINE.

ATTACHED-HANDLE CLOSURE-DISK.

1,313,674.

Specification of Letters Patent. Patented Aug. 19, 1919.

Application filed March 16, 1918. Serial No. 222,844.

To all whom it may concern:

Be it known that I, HARRY L. COMPTON, a citizen of the United States of America, and resident of Washington city, District of Columbia, have invented new and useful Improvements in and Relating to Attached-Handle Closure-Disks, of which the following is a specification.

This invention relates to certain improvements in closure disks and the like; and the objects and nature of the invention will be readily understood by those skilled in the art in the light of the following explanation of the accompanying drawings illustrating what I now believe to be the preferred mechanical expression or embodiment of my invention from among other forms, arrangements and constructions within the spirit and scope thereof.

Milk and other products that are delivered to the consumer in bottles, are usually sealed or closed by flat paper material disks (usually termed "milk caps"), fitted against sealing shoulders or seats within the bottle mouths and held therein by the tension or natural elasticity of the paper material. These disks are exceedingly difficult to remove from the bottle mouths unless provided with pull tabs or handles. These so-called "handle caps" must be of such construction as to permit rapid economical manufacture by automatic machinery and consequent low production cost, and to permit economical packing for shipment, and to reduce to the minimum danger of the handles separating from the disks under the pulling strain during extraction particularly where the handles have been subjected to soaking by milk or other liquid, and to reduce to the minimum the quantity of paper material required, and to avoid so far as possible the use of metal and to render the handles clearly visible and also readily accessible to the fingers. The handle cap commonly employed consists of an oblong flat strip of strong flexible paper, such as tag board, resting on the top face of the paper disk, and at its outer end secured by a staple to the edge portion of the disk, so that the free inner end of the paper strip can be bent up to form a tab or handle for extracting the disk. However, the universal use of these highly desirable handle caps has not been possible because the handles and staples

securing the same to the disks, form upwardly projecting obstructions and edges that prevent the use of such handle caps in bottle capping machinery.

The plain closure disks or caps can be successfully used in such capping machines, but the capping machines on the market cannot be successfully employed for applying the said attached-handle caps or disks of commerce to receptacles. The said attached-handle disks will not feed through such machines and these machines constructed for receiving and applying the plain caps or disks cannot be successfully utilized for manipulating and applying the handle caps because of the projection of the handles and their fastening means beyond the otherwise flat smooth surfaces of the disks. The use of handle caps is thereby to this extent restricted and the public hence to this extent loses the benefits and advantages that would be derived from the use of such handle caps.

Capping machinery is very extensively employed for applying plain "milk caps" to bottles, and for sanitary and other reasons the use of automatic machinery for applying such plain disks is on the increase, and hence for several years the provision of a satisfactory commercial attached-handle cap that could be used in capping machinery, and hence supply the public demand for handle caps, has been a serious problem among closure disk manufacturers and experts.

It is an object of this invention to so improve the said attached-handle cap of commerce that it can be used in capping machinery while retaining all of the advantageous features and qualities of the hereinbefore mentioned handle cap.

A further object of the invention is to so improve said attached handle cap of commerce as to greatly extend the field of use thereof by rendering said cap capable of being applied to bottles by capping machinery, and also to maintain said improvement within such bounds and construction requirements as to permit economical quantity production thereof by the present automatic attached handle cap producing machinery after subjecting the same to comparatively inexpensive additions and modifications.

A further object of the invention is to provide a flat paper closure disk having a handle or tab formed of a separate piece

stapled to the disk and inset therein so that the disk is without such top and bottom projecting edges or shoulders as will prevent the use of capping machinery in applying 5 such disks to bottles and other containers.

The invention consists in certain novel features in construction and in combinations and arrangements as more fully and particularly set forth and pointed out hereinafter.

10 Referring to the accompanying drawings, wherein the disk and other parts are shown exaggerated in size and thickness for purposes of illustration:—

Figure 1, is a perspective of an attached-handle closure disk embodying my invention. Fig. 2, is an edge view.

Fig. 3, is a perspective showing the disk, handle strip, and staple separated.

Fig. 4, is a section radially of the disk and 20 longitudinally of the handle strip.

In the drawings, I show a smooth-faced flat round paper (or equivalent material) disk 1, or so-called "milk cap", having a flat comparatively thin oblong strip of 25 paper 2, (or equivalent material) fastened thereto by staple 3 to form a pull tab or handle. The strip 2 is usually composed of paper of a quality and thickness different from that of the disk. For instance, I prefer to make the handles of tough flexible 30 comparatively thin so-called tag board, although my invention is not so limited. Also I prefer to make the disk and handle of the materials of the same grade and character 35 as now employed in the manufacture of the well known hereinbefore mentioned attached-handle caps of commerce, although I do not wish to so limit my invention.

The flat pull tab or handle, in the example 40 illustrated, has parallel longitudinal edges, is comparatively narrow in width, short in length, and arranged radially of the disk and secured at its outer end to the edge portion of the disk, thereby forming 45 the free inner end that can be bent up and grasped by the fingers in exerting the necessary pull to extract the disk from the mouth of the container closed thereby.

In the example illustrated, the staple 50 securing the handle or tab is U shape and arranged transversely of and driven through the tab and disk with its legs bent against the disk and preferably pressed into the under side thereof in alinement with each 55 other and under and parallel with the top transverse length of the staple, although I do not wish to so limit my invention.

The tab or handle and its securing means (in this example, the staple) are inset or 60 countersunk in the top side of the disk so that the top surfaces of the handle and its securing means are approximately flush with the top surface of the disk *i.e.*, the top surfaces of the handle and its securing

means do not project above or beyond the plane of the top face of the disk and present shoulders, edges or obstructions that will prevent the free use of such caps or disks in bottle capping machinery.

The paper material disk is formed with a 70 top permanent depression, socket, seat or recess *a* to receive the handle and its fastening. In the particular example illustrated, this recess at its outer end opens through the edge of the disk and extends therefrom radially of the disk and is of greater length than the handle. The floor of the recess is flat and parallel with the top face of the disk, except at its inner end *b* beyond the inner extremity of the handle where the 75 depth of the recess gradually tapers off so that the inner end *b* of said floor gradually inclines upwardly to the plane of the surface of the disk.

In the particular example illustrated, the 80 depth and width of the recess more or less closely approximate the thickness and width of the paper strip forming the handle and said strip is more or less snugly fitted therein parallel with the top face of the 85 disk and closely fitting and parallel with the flat portion of the floor of the recess with the top face of the strip not projecting outwardly beyond the plane of the top face of the disk. The edges of the strip preferably 90 fit and protect the vertical raw edge walls of the recess and this engagement can tend to aid in preventing accidental upward flexing of the free end of the strip although I do not wish to so limit all features of my invention. 95

The fastening staple is subjected to pressure which preferably depresses its outer transverse portion approximately below the plane of the top surface of the disk so that 100 said portion of the staple will not form such projections or shoulders as to interfere with the proper operation of the bottle capping machinery. The pressure is so applied to the staple that the transverse portion thereof bodily depresses a corresponding transverse portion 6 of the paper strip (see Fig. 105 4) forming a top groove in which the transverse portion of the staple is inset, and also depressing a corresponding groove in the 110 floor of the recess of the cap immediately above the ends of the staple that are driven upwardly into the bottom of the disk although I do not wish to so limit my invention. 115

The handle strip is thereby strongly 120 secured against separation from the staple during the disk extracting pull while the staple is also strongly held in the disk against separation therefrom during such pull.

The extension of the recess inwardly beyond the inner free end of the handle strip, serves to display or indicate the presence of 125

the handle and its purpose and to guide the finger or finger nail in the operation of elevating the free end of the strip so that it can be grasped by the fingers.

5 Various operations might be utilized to form the depressions in the top sides of the disks, but I gain advantages in forming the recesses through removal of the material of the disk by a rotary grinder or cutter operating at high speed so as not to disintegrate or otherwise disturb and weaken the portions of the disks forming the floors and walls of the recesses. The automatic attached-handle cap making machines now in use, feed a ribbon of disk stock with a step by step movement and at each interval of rest, a handle is stapled to the stock, and a completed attached-handle disk is cut from the stock. A ribbon of handle strip stock 15 is fed into place transversely of the disk stock and between the same and the stapling mechanism during each feeding movement of the disk stock. In adapting such machines to produce the disks of my present invention, I provide means to grind the hereinbefore mentioned recess in the disk stock at each interval of rest and before said recessed portion reaches the handle strip applying position, and provide means 20 requiring accurate registration of the recess with the handle strip and compression or forcing of the handle strip into the recess, although I do not wish to limit my present invention to such apparatus and method, 25 nor do I wish to limit all features of my invention to handle strips formed of paper or secured in the exact manner hereby disclosed.

It is evident that various changes, modifications and variations might be resorted to without departing from the spirit and scope of my invention and hence I do not wish to limit myself to the exact disclosures hereof:

45 What I claim is:—

1. An attached-handle closure disk consisting of a single-ply flat paper-material disk at its top side having a recess formed by a displaced portion of the disk, said recess opening through the edge of the disk and extending therefrom inwardly of the disk, and a straight flexible free-end handle strip of relatively tough material pressed into the previously completed recess and onto the flat floor thereof and clipped to said floor, said separate strip being approximately flush and parallel with the top surface of the disk to permit free use of the disk in capping machinery and to permit ready access to and bending up of the free end of

the strip from the recess to form a pull handle.

2. An attached-handle closure consisting of a paper-material disk having a relatively thin portion of its body cut out and removed to form a top depression or recess extending through the edge of the disk, and a tough flat flexible free-end handle strip set down in said previously completed recess onto the floor thereof and at its outer end stapled in said recess to the edge portion of the disk, the length of said portion cut out and removed exceeding the length of said separate strip, said strip being approximately flush with the top surface of the disk to permit free use of the closure in capping machinery.

3. A single-ply closure disk having a portion of its top side cut out to form an elongated recess extending through the edge of the disk, and a flat handle strip of tough material pressed into said recess and frictionally engaging the sides of the recess and secured to the floor of the recess adjacent to the edge of the disk, said strip being approximately flush with the face of the disk to permit free use thereof in capping machinery.

4. An attached-handle closure consisting of a paper-material disk having a relatively thin portion of its body cut out and removed to form a top depression or recess, and a relatively tough flat flexible free-end handle strip set down in said previously completed recess onto the floor thereof and stapled thereto, the length of said portion cut out and removed exceeding the length of said separate strip, said separate strip being approximately flush and parallel with the top surface of the disk to permit free use of the disk in capping machinery and to permit ready access to and bending up of the free end of the strip from the recess to form a pull handle.

5. An attached-handle closure consisting of a paper-material disk having a relatively thin portion of its body cut out and removed to form a top depression or recess, and a flexible free-end handle strip pressed in said previously completed recess onto the floor thereof and stapled thereto, the side edges of said strip engaging the raw edge walls of said recess, said separate strip being approximately flush and parallel with the top surface of the disk to permit free use of the disk in capping machinery and to permit ready access to and bending up of the free end of the strip from the recess to form a pull handle.

HARRY L. COMPTON.
